UNITED STATES PATENT OFFICE.

EINAR MORTERUD, OF TORDEROD, NEAR MOSS, NORWAY.

METHOD FOR THE LIXIVIATION OF MATERIALS.

Application filed December 6, 1923. Serial No. 679,041.

To all whom it may concern:

Be it known that I, EINAR MORTERUD, a subject of the King of Norway, of Torderod, near Moss, in the Kingdom of Norway, have invented certain new and useful Improvements in Methods for the Lixivation of Materials; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

In the lixiviation of materials a continuous process has been attempted by feeding the material to be lixiviated into the lower part of a vessel, comprising a screening device, while the lixiviation liquid is supplied at the top.

This method has proved to be unsuitable in practice for the reason that it has been impossible to achieve the absolutely necessary parallel movement of evenly distributed material upwards in the vessel.

In order to satisfy this requirement it has been suggested to use a discontinuous process, the material being introduced during one interval of time, the lixiviation taking place in the next interval of time without supply of material.

This object has been sought to be attained by making the screen which covers the whole area of the diffusor reciprocable in a vertical direction, while the feeding takes place in a space which is only filled by liquid and which is obtained by the screen having pressed the material upwards and thereupon returned to a position below the feeding opening.

The feeding accordingly takes place laterally above the screen.

It is obvious that it is impossible to obtain an even distribution of material in this liquid filled space when the material is introduced laterally. The material supplied obviously will be more or less diluted as it moves away from the feeding opening and the result is that the consistency of the material supplied will be uneven, what is exactly what it must not be.

In order to obtain the desired even distribution the only way is to introduce the

material in a diluted condition upwards 55 through the screening surface through particular channels or openings.

This may be obtained either by making the screening surface stationary and using reciprocable piston below this stationary 60 screening surface for effecting the raising movement, or the screening surface itself may form the piston. The screening piston may obviously be provided with holes or channels for letting the material through. 65

In order to prevent a successive filling up of the screening openings it is necessary at intervals to remove the layer of solid material forming at the top of the screening surface. If the material has the form of fibres, fibres 70 will obviously be pressed into the screening opening, and these fibres will adhere to the material on the top of the screening surface so as to form a layer with a more solid character than the material higher up in the 75 vessel.

During the period of displacement the liquid supplied at the top of the vessel will replace the liquor to a certain depth, and the liquor will be pressed out through the 80 screen, the solid material being compressed upon the screen forming a continuous layer. The longer this period lasts, and the quicker the liquor is pressed through the screen, the more solid the layer of material will be. 85

The period of displacement is followed by the period of supply, during which the layer on the screen is lifted somewhat by means of a return movement through the screening holes of a small quantity of liquor. Thereupon a new supply of material is introduced below said layer and upwards until the vessel is completely filled. 90

On the drawings Figs. 1, 1^a, 2, 3, 4 and 5 diagrammatically illustrate some forms of 95 apparatuses for carrying out the invention.

With particular reference to Fig. 1 the vessel A is provided in its lower part by a screen S which is illustrated as comprising a number of narrow screening surfaces with free passages between them. The liquor passing through the screen is collected in a tube a, which passes out through the wall of the vessel and is provided with valve arrangement b. The tube a is provided with a branch c which terminates in a device d, illustrated as a cylinder with piston m which serves the purpose of press-

ing the small quantity of liquor out through the screening openings which is mentioned above and serves to clear the screening openings. B is a movable bottom or piston, provided with flap-valves *e* and reciprocated by means of rods *f*.

In the bottom of the vessel opens a supplying tube *g*, which is covered by flap-valve *h*. Tube *g* leads from the material storage tank C. At the top vessel A is provided with a channel, running round its periphery for taking up the lixiviated material which is removed from the surface of the vessel by means of scraping mechanism *k*, *i*. This scraping mechanism is illustrated as comprising two spiral arms *i*, rotating about a central shaft *k*. Further the vessel is provided near its top with inlet openings *j* for introducing the displacing liquid.

20 The device here described operates in the following manner:

Vessel A is filled with material from C, valves *h*, *e* being opened by means of the pressure of material. Water is introduced through tubes *l*, and valve *b* is opened, whereupon the first lixiviation period starts. Pistons B and *m* are in their bottom position. When the water supplied has displaced so much liquor that the border surface which lies between water (displacing liquid) and original liquor lies between lines *x* and *y*, the lixiviation period is finished and is followed by the supplying period. In the meantime tank C has been supplied with a quantity of material sufficient to cover the requirements of the next supplying period. The overflow edge *n* is adjusted to a level corresponding to this quantity.

40 The supplying period starts with the closing of valve *b* and an upward movement of piston *m*. Hereby a small quantity of liquor is pressed out through the holes of the screen, lifting the layer of material from the same.

Now piston B starts its upward movement, as the piston valves *e* flap back into closed position, while bottom valve *h* opens. The quantity of material above B is now lifted parallelly upwards, being pressed through passages between the screening members and lifting the solid layer of fibres. When this movement ends, the dilution zone *x*—*y* has been lifted to the position *x*₁—*y*₁, and a quantity of lixiviated material mixed with water has been removed into channel D by means of the scraping arms. Below piston B is placed the determined quantity of material from

60 tank C. The valve in the bottom of C is closed, whereupon C is again filled with material, while a new period of lixiviation starts by the opening of valve *b*.

During this period B and *m* return to bottom position, the material as regards B

being pressed through the piston valves coming to rest at the top of piston B. The water (displacement liquid) through tubes *l* may be running continuously (although it is only required during the lixiviation period), and similarly the scraping arms may work continuously. All the movements which are necessary for the alternating lixiviation and supplying periods are taken off a common driving device in any known manner, for instance by means of cam discs, poles, links or the like.

A modified arrangement is illustrated on Fig. 2. According to this form the screening surface is a continuous disc, covering a flat chamber from the bottom of which the outlet tube *a* leads through the bottom of vessel A, being telescopically connected with a co-axial tube in order to enable the screen to be reciprocated so as to act as a piston.

The valves in piston B according to Fig. 1 are on Fig. 2 replaced by an annular opening surrounding the screen and partly filled up by an annular member *r*. This annular member *r* is reciprocated in a vertical direction by means of rods *o*, carrying the screening disc with it. When movement takes place in an upwards direction, the annular body closes the opening, so that the contacts of the vessel above the screen are lifted. When the movement takes place in a downwards direction, the annular slot is opening, so that the material supplied below the screen can be displaced to the upper side thereof.

Further Fig. 2 illustrates an arrangement by means of which the screening openings may be kept clear by causing a pulsation of the liquor below the screening surface.

The arrangement as illustrated comprises an annular diaphragm *g*, which is oscillated by means of rods *p*.

On Fig. 3 is illustrated an arrangement, in which screen and piston form an integral body. The screening surface is perforated by a number of channels *m*, which may all be closed by means of valves *e*, mounted on a screen which is again reciprocated by means of rods *o*.

When the piston moves in a downward direction, valves *e* open for channels *m* until the screen carrying valves *e* abut against collar *n* on rod *a*. Then the screening surface is also pulled downwards to its bottom position. During the upward movement of rods *o* the screening plate is pressed upwards, valves *e* closing the channels *m* therein.

In order still further to secure an even mixture of liquid and material, the apparatus may be provided with a stirring apparatus, having arms *t* rotating in horizontal planes.

This arrangement is illustrated on Fig.

4. The shaft *k* for the scraping arm *i* is extended downwards and provided with stirring arms *t*.

If stirring of the material below the surface is desired, the shaft as indicated in dotted lines may be extended below the screen and provided with arms on the underside thereof.

A rotating stirring shaft *u* may also be introduced from the bottom of the vessel as illustrated on Fig. 5, the shaft passing freely through bottom valve *h*.

On Fig. 5 it will be noted that the piston *B* is placed in a horizontal cylinder communicating through a tube *G* with the bottom of the vessel *A*. The tube *g* from the tank *C* (not shown of Fig. 5) communicates with the said horizontal cylinder, and the piston *B* is provided with flap valves in the same manner as in Fig. 1, although this is not shown on the drawing.

The object for placing piston *B* in the particular cylinder is to permit free working of the stirring arms *t*.

25 The screen tube *a* is connected with pulsation cylinder *d*, as illustrated on Fig. 1, although this pulsation cylinder is omitted on the drawing for the sake of clearness.

Claims:—

30 1. In a process of lixiviation of materials in a vessel provided with a screen covering its whole cross sectional area and where periods of feeding alternate with periods of lixiviation, the method which consists in introducing the material into the space above the screen from the underside of the screening surface through openings in the screening surface for the purpose of obtaining a mixture of the same consistency above 35 the whole of the screening surface, and of removing the solid deposits on the screening surface by means of the new material introduced through the same.

2. An apparatus for use in lixiviation of 45 materials, comprising a vessel, a screen therein, covering substantially the cross sectional area of said vessel, means for introducing the material to be lixiviated into the vessel below said screen and means for pressing 50 the said material upwards through openings in the screening surface.

3. An apparatus for use in lixiviation of 55 materials, comprising a vessel, a screen therein, covering substantially the cross sectional area of said vessel, means for introducing the material to be lixiviated into the vessel below said screen and means for introducing diluted liquid (water) above the said screen and a reciprocating piston for 60 pressing the said material upwards through openings in the screening surface.

4. An apparatus for use in lixiviation of

materials, comprising a vessel, a screen therein, covering substantially the cross sectional area of said vessel, means for introducing the material to be lixiviated into the vessel below said screen, a reciprocating piston for pressing the said material upwards through openings in the screening surface and means for scraping the diluted 65 material off the top of the vessel.

5. An apparatus for use in lixiviation of 70 materials, comprising a vessel, a screen therein, covering substantially the cross sectional area of said vessel, means for introducing the material to be lixiviated into the vessel below said screen, means comprising rotating arms for stirring the material in the said vessel and a reciprocating piston for pressing the said material upwards 75 through openings in the screening surface.

6. An apparatus for use in lixiviation of 80 materials, comprising a vessel, a screen therein, covering substantially the cross sectional area of said vessel, a reciprocating piston below the said screen, means for introducing the material to be lixiviated below the said reciprocating piston, said means comprising a one-way valve, and one-way valves in the said reciprocating piston for 85 enabling the piston to press the said material through openings in the screening surface.

7. An apparatus for use in lixiviation of 90 materials, comprising a vessel, a screen 95 therein, covering substantially the cross sectional area of said vessel, stirring means, comprising rotating arms in the vessel below the said screen, means comprising a cylinder and reciprocating piston for intermittently introducing material to be lixiviated under pressure into the said vessel 100 below the screening surface.

8. An apparatus for use in lixiviation of 105 materials, comprising a vessel, a screen therein, covering substantially the cross sectional area of said vessel, said surface comprising a number of parallel screen ribbons or strips, forming the top of narrow channels which communicate with an outlet tube 110 for lixiviation liquid, means for producing back pressure in said outlet in order to cleanse the screening surfaces, means for introducing the material to be lixiviated into the vessel below said screen and a reciprocating piston for pressing the said material 115 upwards through openings in the screening surface.

In testimony that I claim the foregoing 120 as my invention, I have signed my name in presence of a subscribing witness.

EINAR MÖRTERUD.
